FLAT PAD APPLICATOR FOR PAINT AND THE LIKE

Robert C. Nicolay, Wooster, Ohio, assignor to The Wooster Brush Company, Wooster, Ohio, a corporation of Ohio

Filed Aug. 5, 1968, Ser. No. 13,036

Term of patent 14 years

Int. Cl. D18—99

U.S. Cl. D64—18

FIG. 1 is an isometric view of a flat pad applicator for paint and the like as seen from the front left corner;

FIG. 2 is a top plan view on a reduced scale of the flat pad applicator for paint and the like of FIG. 1;

FIG. 3 is an end elevation view on a reduced scale as seen from the right end of FIG. 1;

FIG. 4 is a rear elevation view on a reduced scale; and

FIG. 5 is a bottom plan view on a reduced scale.

The dominant features of my new design reside in the portions shown in full lines.

I claim:

The ornamental design for a flat pad applicator for paint and the like, substantially as shown and described.
